UNITED STATES PATENT OFFICE.

RUDOLF FRIES, OF BERLIN-SCHONEBERG, GERMANY.

SOUND-DEADENING CASE FOR TYPEWRITERS, CALCULATING MACHINES, AND THE
LIKE.

Application filed May 11, 1922. Serial No. 560,219.

To all whom it may concern:

Be it known that I, RUDOLF FRIES, a citizen of the German Republic, residing at Berlin-Schoneberg, Wartburgstrasse 23, Germany, have invented certain new and useful Improvements in and Relating to Sound-Deadening Cases for Typewriters, Calculating Machines, and the like, of which the following is a specification.

10 The object of the present invention is a sound deadening case for typewriters, calculating machines and the like.

The essential feature of the invention consists therein that the sound-deadening case is formed of two parts, which are fixed to each other by a connection, which may be easily unfastened for renewal of the parts or for other purposes; one of said parts, say the base part, being adapted to contain the 15 main body of the typewriter, calculating machine or the like, with the platen, the writing mechanism, the paper-carriage and adjoining parts, while the other part covers the keyboard and adjoining levers of the 20 machine. This division of the sound-deadening case into two parts enables the same base portion to be used for different sorts of typewriters, so that only the other or front part of the case requires to be altered 25 to fit the particular type of machine. Further, this construction permits of a quick 30 operation of the keyboard of the machine and an easy adjustment of such parts of the keyboard and leverage which might have 35 got out of order.

Another essential feature of the invention consists therein, that the above mentioned main or base part of the casing is sub-divided into two parts namely the fixed 40 lower frame or cover enclosing the corresponding parts of the typewriter or other machine and an upper movable cover, which is hinged to the rear-wall of the lower frame or cover, and which upper cover may be 45 pivoted on hinges so as to allow of instantaneous access to the paper-carriage and to the writing mechanism if such parts should need any adjustment or repair. Other characteristic features of the invention are that 50 the sound deadening case may be readily fixed to the usual base-board of the machine, preferably by means of screws, clamps, bolts or other suitable means although the base-board can be dispensed with. For fixing 55 the machine to the bottom part of the

case, the lower frame or cover may be provided at its lower inner side with a flange or rim or with parts forming an inner lower flange or rim on to which are clamped the said screws or clamps to hold down the machine. 60

In order that the invention may be readily understood, I have shown in the drawings a preferred embodiment of the new sound-deadening case, in which:—

Figure 1 is a vertical section on line A—B of Fig. 2, the cover of the sound deadening case being closed; Fig. 2 is a plan view of same parts being shown in horizontal section; Fig. 3 is a vertical section similar to Fig. 1, but without front portion, and without a typewriter machine being shown in the case; the movable cover can be swung back as indicated by dotted lines. 65

According to the construction shown, that part of the sound deadening case which covers the main-body of the typewriter consists in the central cover or frame 1, to which is hinged the movable cover 2, in the front part of which is provided a window 3. The front portion 4, containing dummy-keys is secured dust-proof to the central portion of the cover or frame by sliding same laterally into guideways 5 of the central cover, and by a front bar 13 and two or more fastening screws 6, 7 whereby the front part is screwed down to the base-plate. The particular shape of this front part 4 varies according to the kind of keyboard of the particular machine, but the position of the guideways 70 80 85 90 95 100 105 110

5 and of the fastening screws 6, 7 are the same for any kind of front parts, in order to standardize the cases for a number of types by the use of interchangeable portions. The typewriter, which is indicated by dotted lines, rests, by means of rubber feet, on the wooden base-board 11, the front and the back of which are provided with bars 12, 13 serving as locating stops for the sound deadening case 1. The movable cover 2 of the case may be swung round on its axis 14, which is arranged at the lower part of the rear-wall of the central frame or cover 1, in order that by swinging back the cover 2 the operator of the machine can expose the paper on the carriage 10 for corrections or the like instantaneously. A typewriter eraser 16 is fixed to the cover 2 say at 18 by means of an extensible holder 17. If the cover 2 is closed and the machine is not in use, the cover 2

may be locked to prevent the machine being removed without destroying the entire cover. For the same purpose the bolts 19, which are provided at the lower inner brim of the sound deadening case, and which may engage into corresponding ears at the base-plate 11 are provided. The front part 4 may be fixed to the central frame or cover 1 by similar bolt and ear connections or locks, which when in locking position, if the case and its base-plate are sufficiently strong, and fixed to the typewriting table or desk, then the machine is secure against theft.

I claim:

1. Sound deadening case comprising in combination, a fixed lower central cover surrounding the main body of a machine with its platen, the writing mechanism, the paper-carriage and adjoining parts of the machine, a movable upper cover, hinged to the rear-wall of lower cover, and adapted to be swung up and back round its hinges to give instantaneous access to the paper-carriage and to the writing mechanism, an interchangeable front portion to cover the keyboard of the machine, means for securing same dust-proof to the open front side of the central

cover and a keyboard having dummy-keys operating the ordinary keys of the machine, substantially as described and illustrated. 30

2. Sound deadening case comprising in combination, a fixed lower central cover surrounding the main-body of the machine with the exception of the keyboard, a hinged upper cover, on said central cover, a window in an inclined front side of said upper cover for permanent inspection of the writing mechanism and paper carriage, of the machine, an interchangeable front portion surrounding the keyboard of the machine secured dust-proof to the open part of the front portion of the central cover, a dummy-keyboard in said front portion adapted to operate the ordinary keys of the machine; detachable means at the inner side of the sound deadening case for fastening the case to the base-plate of the machine, which detachable means are not accessible from the outside of the case, and locks for locking the movable upper cover and the interchangeable front portion when the whole sound deadening case is put together and is closed. 45 50

RUDOLF FRIES.
